UNITED STATES PATENT OFFICE.

JESSE L. TURNER, OF MORGANTOWN, WEST VIRGINIA.

DESIGN FOR A BOWL FOR GOLDFISH.

51,663.

Specification for Design.

Patented Jan. 1, 1918.

Application filed June 6, 1917. Serial No. 173,243. Term of patent 14 years.

To all whom it may concern:

Be it known that I, JESSE L. TURNER, a citizen of the United States, residing at Morgantown, in the county of Monongalia and State of West Virginia, have invented a new, original, and ornamental Design for Bowls for Goldfish, of which the following is a specification, reference being had to the accompanying drawing, forming part thereof.

The figure is a side elevation of a bowl for gold fish, showing my new design.

I claim:

The ornamental design for a bowl for gold fish, as shown.

JESSE L. TURNER.

Witnesses:

W. LOYD MORRIS,
CHAS. H. JOHNSON.
